CLAIM

The ornamental design for an automotive lamp, as shown and described.

DESCRIPTION

FIG. 1 is a front elevational view of an automotive lamp showing my new design;

FIG. 2 is a first perspective view thereof;

FIG. 3 is a second perspective view thereof;

FIG. 4 is a top plan view thereof; and,

FIG. 5 is a bottom plan view thereof.

The broken lines depict portions of the automotive lamp that form no part of the claimed design.
